UNITED STATES PATENT OFFICE.

CHARLES H. MEISTER, OF BELLAIRE, OHIO.

MINER'S CAP AND LAMP CONNECTION.

Application filed February 16, 1922. Serial No. 537,091.

To all whom it may concern:

Be it known that I, CHARLES H. MEISTER, a citizen of the United States, residing at Bellaire, in the county of Belmont and State of Ohio, have invented new and useful Improvements in Miners' Cap and Lamp Connections, of which the following is a specification.

The object of my said invention is the provision of a simple and strong construction for the detachable connection of a lamp to a miner's cap, and one which will permit of ready connection and disconnection of the lamp with one hand, and this without liability of the lamp being casually disconnected and displaced or moved when the miner stoops or otherwise moves his body or head.

To the attainment of the foregoing, the invention consists in the improvements as hereinafter described and definitely claimed.

In the accompanying drawings, forming part of this specification:—

Figure 1 is a side elevation showing my improvement in use.

Figure 2 is an enlarged vertical section of the same.

Figure 3 is a detail transverse section taken in the plane indicated by the line 3—3 of Figure 1.

Figures 4 and 5 are perspectives of the body plate and reenforcing plate, respectively, of the improvement.

Figure 6 is a perspective of the spring.

Figure 7 is a detail perspective of the lamp member.

Similar numerals designate corresponding parts in all of the views of the drawings.

In accordance with my invention the lamp 1, Figures 1 and 2 is provided at its back with a member 2, preferably of sheet-brass, fixed at its ends to the lamp.

The said member 2 is equipped at 3 with a rearwardly projecting stud which includes a shank 4 and a head 5, both in rear of the vertically-disposed portion of the member 2 and appropriately fixed to said portion. The head 5 shown in Figures 2 and 7 is rounded at its rear side and flat at its forward side while the shank 4 is of rectangular shape in cross-section.

The cap 6 shown in Figures 1 and 2 is provided with a visor 7 and is otherwise of the ordinary miners cap construction or of any other type compatible with the purpose of my invention.

The cap portion of my improvement comprises a body plate 8 and a reenforcing plate 9 both of which are made of appropriate sheet-metal, galvanized when deemed expedient. The plate 8 comprises an intermediate, upright portion that rests against and is attached at 10 to the front of the cap body, an upper horizontal portion that rests on the cap crown and is connected thereto at 11, and a lower inclined portion that rests solidly on the visor 7 and is attached at 12 to the same. For the stiffening of the body plate 8 the longitudinal edges of the same are preferably folded forwardly and inwardly as designated by 13. In the center of the apex of the angle formed by the intermediate and upper plate portions is formed an opening 14 sufficiently large for the vertical movement through the same of the stud head 5, and in the intermediate plate portion is formed a contracted slot 15 of a size to snugly receive and seat and hold the stud shank 4. The angular re-enforcing plate 9 is interposed and secured between the edge portions 13 of the plate 8, and is provided with an opening 14^x and a depending slot 15^x, registered with and corresponding in size to the opening 14 and slot 15, respectively, of the plate 8.

Fixed at 16 to and carried at the back of the intermediate portion of the plate 8 is the shank 17 of a curvilinear spring 18 positioned in rear of the openings 14 and 14^x and the slots 15 and 15^x as clearly shown in Figure 2.

Vertical movement of the lamp 1 and its member 2 of the cap wearer is all that is necessary to couple the stud 4—5 to or uncouple said stud from the plates 8 and 9. Manifestly when the stud head 5 is moved downwardly through the openings 14, 14^x, and the rectangular stud shank 4 is seated in the slots 15, 15^x, the lamp will be strongly connected to and supported by the cap without liability of casual disconnection of the lamp or sidewise movement thereof. To detach the lamp from the cap it is simply necessary for the miner to reach up with one hand and move the lamp straight upwardly, relative to the cap, when the disconnection will be effected by the upward passage of the stud out of the slots 15, 15^x, and through the openings 14, 14^x.

When the lamp is connected to the cap as appears in Figure 2, the spring 18 strongly though yieldingly presses the flat

side of the stud head 5 against the rear side of the plate 8 to render the connection tight and at the same time the said spring 18 holds the stud against upward movement, some little stress being necessary to move the stud home in attaching the lamp and to move the stud upwardly for the disconnection of the lamp.

I have entered into a detailed description 10 of the construction and relative arrangement of the parts embraced in the present and preferred embodiment of my invention, in order to impart a full, clear and exact understanding of the said embodiment. I do not 15 desire, however, to be understood as confining myself to the said specific construction and relative arrangement of parts inasmuch as in the future practice of the invention various changes and modifications 20 may be made such as fall within the scope of my invention as defined in my appended claims.

Having described my invention, what I claim and desire to secure by Letters-Pat- 25 ent, is:—

1. A cap and lamp connection comprising a body plate attached to a cap and having an upright portion and a top portion extending rearwardly at an angle to the up- 30 right portion and also having an opening in the apex of the angle formed by said portions, and a slot formed in the upright portion and extending downwardly from said opening, a curvilinear spring arranged 35 back of said slot and carried by the up- right portion of the plate, and a member

carried by a lamp and having an upright portion to rest against the upright portion of the body plate and also having a rearwardly extending stud with a shank, of 40 rectangular form in cross-section, and a head flat at its forward side and rounded at its rear side.

2. A cap and lamp connection comprising a body plate attached to a cap and having an upright portion and a top portion extending rearwardly at an angle to the upright portion and also having an opening in the apex of the angle formed by said portions, and a slot formed in the upright 45 portion and extending downwardly from said opening, a curvilinear spring arranged back of said slot and carried by the upright portion of the plate, and a member carried by a lamp and having an upright 50 portion to rest against the upright portion of the body plate and also having a rearwardly extending stud with a shank, of 55 rectangular form in cross-section, and a head flat at its forward side and rounded 60 at its rear side; the said body plate having its longitudinal edges folded inwardly and being combined with an angular reenforcing plate fixed thereto and arranged between said folded edges and having an 65 opening and a slot corresponding in size to and registered with the opening and slot, respectively, of the body plate.

In testimony whereof, I affix my signature.

CHAS. H. MEISTER.
